SPRING COUNTERBALANCED SASH

August Huttger, Tioga, Pa., assignor to
Edward P. Huttger, Philadelphia, Pa.Original application June 28, 1934, Serial No.
732,891. Divided and this application January
11, 1935, Serial No. 1,274

2 Claims. (Cl. 16—201)

This invention relates to spring counterbalanced sash in which a torsional spring or springs, is or are, put under strain when the sash is closed and when opened exert force upon connected mechanism to aid the opening operation, and hold the sash in the desired position.

Specifically the instant case is a division of my copending application for patent filed June 28, 1934, under Serial Number 732,891, on "Metal window frame and sash construction", and it has for its primary object the provision of a novel spring counterbalance assembly whereby the associated sash is more easily operated than heretofore.

Another object is to provide a spring counterbalance for metal window frame and sash which is of a very durable construction while positively stabilized in action under all normal conditions.

With the stated and ancillary objects in view as will hereinafter become apparent, or be specifically referred to, this invention consists in the features of construction, combination and arrangements of parts, all as particularly set forth and more specifically defined in the claims.

In the drawings:

Fig. I is a broken partial-elevation of a metal window frame and sash construction embodying the spring counterbalance of the present invention, looking from the inside outwards and with the frame jamb in lateral section to better disclose the counterbalance mechanism.

Fig. II is a vertical section taken on the plane designated II—II in Fig. I.

Fig. III is a broken and enlarged detail section of the upper sash operating mechanism.

Fig. IV is a fragmentary perspective view of a top corner of the upper sash with a portion of the associated operating rack.

Fig. V is a sectional view corresponding in the main with Fig. III, but illustrating a modified form of the operating-spring stabilizing means.

Fig. VI is a somewhat similar view of a further type of spring stabilizer.

Fig. VII is a perspective view of a stepped bracket, hereinafter fully described.

Fig. VIII is a perspective view of a sleeve-like member, later on described in detail; and,

Fig. IX is a perspective view of a composite gear, also hereinafter fully explained.

Like characters of reference are applied to corresponding parts in all the views.

Referring first and with more particularity to Figs. I and II, and also in part to Figs. III and V,

which show portions of a window frame and sash construction in accordance with the prior application for patent, hereinbefore referred to and of which the instant case is a division, the reference numerals 1, 2 respectively designate the upper and lower sash of a sheet metal window structure; 3 indicates the left-hand frame jamb-box; 4 the head, and 5 the sill; all of which are preferably constructed in accordance with the noted prior application.

The means for operatively controlling the respective sashes 1, 2 and which constitute the subject-matter of the instant case comprise a stepped bracket 6, one of which is attached within each frame jamb-box 3, as by screw-bolts 7, Figs. I—IV; the left-hand side of the window only being shown as the right-hand side is a counterpart thereof, and in order to avoid unnecessary descriptive matter. This bracket 6 is formed with a bearing 8 for a pin or axis 9, on which is freely journaled an integral, or composite, spur gear 10 and miter-pinion 11; the former of which meshes with the associated upper and lower sash rack 12, as best understandable from Fig. II. The respective miter-pinions 11, on the other hand, mesh with corresponding pinions 13 integral with the lower ends of sleeve-like members 14, freely supported on a vertical extension 15 forming a part of each associated stepped bracket 6. Each sleeve-like member 14 is prevented from vertical, or axial, displacement by means of a headed pin 16, fitted into an axial boring 17 of the upstanding bracket extension 15, and a diametric cotter pin 18, as best shown in Fig. III; while diametrically-opposed holes 19 are provided in the sleeve members 14 for ease in assembling or disassembling said parts.

Each sleeve-like member 14 is provided near its upper end with a lateral flange 20 and a vertically-directed annular portion 21, both concentric with the axis thereof, and jointly affording bearing for a thin tube 22, functional as a stabilizer for a torsional spring 23; said spring having its lower extremity 24 passed through a suitable hole 25 in the lateral flange 20. The tube 22 extends coaxially of the spring 23, and its upper portion slidingly cooperates with an inverted cup 26 securely attached, as by a rivet 27 to the horizontal portion 28 of the window frame head 4, while the torsional spring 23 has its upper extremity passed through a hole 29 therein and clinched over at 30, in an obvious manner. Thus it will be readily seen that each tube 22 functions as a floating-support or centralizing-

stabilizer to retain the associated spring 23 in correct operating alignment.

Instead of the tube 22 being slidably-fitted internally of the associated spring 23, as shown in Figs. I, II and III, it may be floatingly-supported intermediate the sleeve member annular portion 21 and the inverted cup member 26, as indicated in Fig. V; or, it may be similarly supported by the sleeve member lateral flange 20, and located 10 outside the spring 23, as indicated in Fig. VI, when so repositioned or deemed advisable.

From the foregoing description and drawings the operation of my improved spring counterbalance for metal sash will be self-evident to those 15 acquainted with the art, without detailed explanation herein.

It will likewise be apparent from the preceding disclosure that the invention is well calculated to adequately fulfil the objects preliminarily 20 stated; while it is to be further understood that changes and variations may be effected within the spirit and scope of the following claims and so far as the prior art proscribes.

Having thus described my invention, what I claim, and desire to secure by Letters Patent, is:—

1. In a device of the class described, the combination of a bracket adapted to be attached to the window frame, said bracket having an extension thereon, a rack on the sash, a sleeve rotatable on the extension, a headed pin having axial engagement in the sleeve, means for interlocking the pin with the sleeve to prevent relative axial movement thereof, said sleeve having 10 a lateral flange, a cup member fixed to the head of the window frame, a tube movable relative to the cup member at its upper end and engageable with the sleeve at its lower end, a spring having one terminal fixed to the window frame 15 and its other terminal fixed to the said flange, said tube serving to retain the spring in axial alignment at all times, and a geared connection between said rack and sleeve.

2. A device as claimed in claim 1, wherein the 20 means for interlocking the headed pin with the extension consists of a pin engaged in the extension and headed pin.

AUGUST HUTTGER.
